UNITED STATES PATENT OFFICE.

JUSTIN NEU, OF NUREMBERG, GERMANY, ASSIGNOR TO ELECKTR-BOGENLAMPEN-& APPARATE-FABRIK GES. M. BESCHR. HAFTUNG.

HOISTING DEVICE FOR ELECTRIC-ARC LAMPS.

No. 863,041.

Specification of Letters Patent.

Patented Aug. 13, 1907.

Application filed November 9, 1906. Serial No. 342,671.

To all whom it may concern:

Be it known that I, JUSTIN NEU, of Nuremberg, a subject of the King of Bavaria, and whose post-office address is No. 11 Königstorgraben, Nuremberg, Bavaria, German Empire, have invented a new and useful Improved Hoisting Device for Electric-Arc Lamps, of which the following is a specification.

The present invention relates to a hoisting device for electric arc lamps and has for its object a hoisting apparatus by means of which an arc lamp can be raised and lowered and automatically switched into and cut out of the electric circuit by means of a pull-cord, strap, band, rope, chain, wire or equivalent flexible draft-means or pulling device which is connected with the hoisting device only during the time during which the lamp is being raised or lowered, whereas the hoisting device itself is permanently provided with only a short pull-cord, strap, band, rope, chain, wire or the like equivalent flexible pulling-device or draft-means, from which the lamp is suspended.

A further object of the present invention is to provide means for holding up the lamp while it is being raised or lowered, said means in any case holding or locking the lamp securely if the cord, band or the like is released.

In order that the details of construction and action of the invention may be clearly understood, reference is made to the accompanying drawing in which one form of the hoisting device is shown by way of example, and in which:

Figure 1 is a side elevation of the device, the case being shown in section; Fig. 2 shows an end elevation of the device with the case in section on the line 2-2 in Fig. 1; and Fig. 3 shows a detail end elevation of the upper part of the means for hooking the detachable band into the short band on the hoisting apparatus.

Similar letters of reference refer to similar parts in all views.

A head-plate *n* forming part of the frame of the device and which may be fastened in any suitable manner to the ceiling or other suitable support carries the arms *p*, *p* in which a pulley or drum *a* is mounted revolvably and also a second guide pulley *f*. A lever *b* which has a wedge-shaped head *k* at the one end and a revolvable pulley *c* at the other end is mounted revolvably above the pulley *a*. A short band *h* which is fastened by means of an angle iron *o* to a plate *e* on the body of the lamp runs over the pulleys *f*, *a*, and *c*. A yoke or bridge *d* or like abutment is attached to the arms *p* in such a manner that the wedge-shaped head *k* of the lever *b* jams between the bridge part of the yoke *d* and the periphery of the pulley *a* over which the band *h* runs, when said lever *b* is in the position shown in full lines in Fig. 1. A spring *g* tends to hold the lever *b* constantly in the position indicated in full lines. 55

The plate *e* of the body of the lamp is provided with electric contact pillars *m*, *m*¹ which slide into corresponding electric contact sleeves *l*, *l*¹ the latter being fastened to the head-plate *n* of the hoisting device. A case *r* incloses the device, openings being provided in the same through which the band *h*, the pulley *c* and the contact pillars *m*, *m*¹ pass as represented in the figure. The lamp is switched into or cut out of the electric circuit respectively, according as the contact pillars *m*, *m*¹ are at their highest position in the sleeves *l*, *l*¹, or as 60 the body of the lamp with the plate *e* and the contact pillars are lowered.

The short strap or band *h* is provided at its free end with a hook *i* or the like into which the eye *t* of a long strap or band *s* can be hooked. When this band is 65 hooked on to the hook *i* and pulled downwards, the pulley *c* is pressed downwards, and when the band *s* is somewhat slackened again the plate *e* with the body of the lamp is lowered, the short band *h* and its continuation, *i. e.* the long band *s* running over the pulley 70 *a*. At the very moment at which the band is let go, the pulley *c* is relieved of pressure and the spring *g* pulls the wedge-shaped head *k* of the lever *b* downwards between the periphery of the pulley *a* and the bridge of the yoke *d* whereby the band is clamped and 75 the lamp is prevented from descending. The long band *s* may be hooked into the hooks *i* by using a rod *w* which is carried by the attendant and which is fitted with a double leaf-spring *v* at its head, between the leaves of which the upper end of the band *t* is clamped. 80 The hoisting device in accordance with the present invention has besides others also the advantage that one single long band can be used which the attendant carries about with him for use with all the arc lamps of a plant or of a room, whereas the hoisting device itself 85 has only the short band *h*. In the embodiment illustrated by way of example a flat strap or band is provided; but of course a rope, cord or chain may be employed instead; in the latter case the pulley *a* will be formed in known manner as a chain-pulley, and the 90 head *k* of the lever *b* will be correspondingly provided with teeth to engage the links of the chain. In like manner the short band *h* or the chain may, of course, have an eye and the long band *s* or chain may be provided with a hook, and similar constructional variations 95 may be devised without departing from the spirit and scope of the present invention. 100

What I claim, and desire to secure by Letters Patent of the United States, is:—

1. A hoisting device for electric lamps, comprising in 105 combination a frame, a short flexible pulling device, means

connecting the same with the lamp, a pulley on the hoisting device for guiding said pulling device, a long portable flexible pulling device, means for detachably connecting said long portable pulling device with the short pulling device whereby the former while in use forms a detachable continuation of the latter, a spring-actuated pivoted lever provided with an arm having a clamping head, a pulley revolvably mounted on said lever over which pulley the interconnected pulling devices run, and an abutment provided on the frame in proximity to the edge of the pulley first mentioned above, said clamping head being normally between said abutment and pulley-edge under the spring-action whereby whenever the interconnected pulling devices are let go said head takes up its normal position and locks the lamp in its position occupied at the time, said head being disengaged from the pulley while the pulley pulling devices are being operated.

2. A hoisting device of the type described for electric lamps, comprising in combination a frame, a short strap provided with a hook at one end, means connecting the other end of said strap with the lamp, a pulley for guiding said strap, a long portable strap provided with an eye engaging said hook on the strap so that the long strap while in use forms a detachable continuation of the short strap, a pivoted lever, a spring acting on said lever, said lever being provided with an arm having a wedge-shaped head, a pulley revolvably mounted on said lever, over which pulley the interconnected pulling devices run, a yoke in proximity to the edge of the pulley, said clamping head being normally between said yoke and pulley under the action of the spring whereby whenever the pulling-devices are let go

said head takes up its normal position and locks the lamp in its position occupied at the time, said head being disengaged from the pulley while the pulling-devices are being operated.

35

3. A hoisting device of the type described for electric lamps, comprising in combination a frame having a head-plate, provided with contact sleeves, and two arms, two pulleys mounted on the latter, a short strap passing over said pulleys and provided with a hook at one end, means connecting the other end of said strap with the lamp, a long portable strap provided with an eye engaging said hook on the strap so that the long strap while in use forms a detachable continuation of the short strap, a pivoted lever, a spring acting on said lever, said lever being provided with an arm having a wedge-shaped head, a pulley revolvably mounted on said lever, over which pulley the interconnected pulling devices run, a yoke in proximity to the edge of the pulley, said clamping head being normally between said yoke and pulley under the action of the spring whereby whenever the pulling-devices are let go said head takes up its normal position and locks the lamp in its position occupied at the time, said head being disengaged from the pulley while the pulling-devices are being operated.
